REGISTERING AND COMPUTING
MECHANISM

Joseph C. Woodford, Wayne, Pa., assignor to John
Wood Manufacturing Company, Inc., Con-
shohocken, Pa., a corporation of Delaware

Application May 15, 1941, Serial No. 393,504

8 Claims. (Cl. 74—283)

My invention relates to counters of the computing type which are particularly adaptable for use in apparatus used for dispensing gasoline into tanks of automobiles. Most of such liquid dispensing apparatus as are currently purchased for use in service stations include counters adapted to indicate both the quantity and total cost of the gasoline dispensed. Such apparatus includes a variator which may be pre-adjusted to compute the cost of the quantity of the fluid dispensed in accordance with a visible dial-indicated current price, and my invention more particularly relates to the means for setting the variator.

It is an object of my invention to provide improved means, interconnected with the displayed invisible price indicators, for pre-adjusting or setting the variator so that the displayed total cost of any fluid dispensed must be computed at the price displayed at the visible price indicators.

Another object of my invention is to provide means to simultaneously disengage the tenths cent, cent, and tens of cents selector gears from mesh with the variator cone gear, by a single movement of said means, thus permitting any or all of said selector gears to be moved to changed position with facility by mere turning movement of setting knobs.

Still another object of my invention is the locating at the bottom of the front of the counter mechanism where readily and facilely accessible to the operator, of both the setting knobs and the means to effect disengagement of the selector gears.

A further object of my invention is to provide simplified operating means whereby the current price indicia contemporaneously are set to coincide with a changed setting of the variator.

The counter zeroizing or resetting mechanism shown and disclosed herein forms the subject-matter of and is claimed in my copending application Serial No. 381,989, filed March 6, 1941.

My invention includes the various novel features of construction and arrangement herein-after more definitely specified.

Fig. I is a vertical sectional view of a computing unit embodying my invention, taken on the lines I, I in Figs. II and III.

Fig. II is an elevation of the left hand end of the structure shown in Fig. I, but with the side bearing plate removed.

Fig. III is an elevation of the right hand end of the structure shown in Fig. I.

Fig. IV is a front elevation of the structure shown in Fig. I and including the dial plate hav-

ing apertures therein through which the number wheels are visible.

Fig. V is a skeletonized plan sectional view illustrating the variator price changing mechanism, but showing only the tenth cent selector gear and its appurtenances.

Referring to the drawings; the setting means by which changes in the setting of the variator may be effected manually, are indicated generally within the lines carrying the reference mark A. The variator mechanism through which the quantity of fluid dispensed, at a pre-adjusted price, is translated into total cost, is indicated generally within the lines carrying the reference mark B. The mechanism for indicating the price at which the variator is set to compute is indicated generally by the reference mark C. The counter mechanism, conveniently a gallons register, for indicating the quantity of fluid dispensed, is indicated generally within the lines carrying the reference mark D. The counter mechanism for indicating the total cost of the quantity of fluid dispensed is indicated generally within the reference mark E.

25 The primary drive shaft 1 is adapted to be connected by means of the coupling 2 with the driven shaft 3 of a conventional type of liquid meter as used in liquid dispensing apparatus of the type for which my invention is particularly applicable. Said shaft 1 is journaled in the bearing bracket 4 on the bottom closure plate 5, which forms part 30 of the housing for the counter mechanism. Said housing also includes the upper plate 6 and the side frames 8 and 9 conveniently held together by means of a series of screws 10.

Said shaft 1 carries the bevel gear 11 conveniently fastened on said shaft 1 by means of the pin 12. Said bevel gear 11 is in mesh with the bevel gear 13 carried by the shaft 14 and conveniently fastened on said shaft by means of the pin 15. Said shaft 14 is journaled in the bearings 16 and 17 conveniently formed as bosses on said bottom plate 5. Said shaft 14 carries at 45 its opposite end the gear 18 conveniently fastened on said shaft by means of the pin 19. Said gear 18 is in mesh with the gear 20 rigidly fastened by screws 21 to the housing 22 of the friction clutch of the quantity counter. Said clutch housing 22 is carried by the left hand end of the sleeve, or hollow shaft, 24, the right hand end of which is journaled in the side frame member 9.

The friction clutch is of conventional type and includes the clutch springs 25, clutch levers 26, pressure ring 27, clutch driving plate 28, and

disk 29, which disk is interposed between the clutch plate 28 and said gear 20.

Said hollow shaft 24 carries the clutch releasing plunger 31, the right hand end of which extends beyond said side frame member 9 for engagement with the bell crank lever 32. The plunger rod 31 has mounted on the left hand end thereof the thimble 33 for engagement with the clutch levers 26, when said rod is moved, to the left, as a result of turning movement of the crank 35 which effects operation of the zeroizing mechanism. Said thimble 33 is mounted for reciprocal movement in the bushing 34 carried by the left hand side frame member 8.

The counter mechanism is of ordinary construction and includes the gears 36, 37, and 38 mounted on said hollow shaft 24, and the tens transfer pinions 39 and 40. The transfer pinion 39 is loosely mounted on the shaft 41 rigidly supported in the bosses 42 formed on the bottom closure plate 5. Said transfer pinion 40 is loosely mounted on the shaft 44 rigidly supported in the bosses 45, also formed on the bottom closure plate 5.

Said quantity counter generally indicated at D includes two oppositely counterpart series of numbered wheels, one complete series of which is shown in Fig. I, including the counter wheel 46 of lowest order and conveniently carrying indicia indicating tenths of a gallon, the counter wheel 47 of next higher order, conveniently carrying indicia indicating whole gallons, and the counter wheel 48 of highest order, conveniently indicating tens of gallons. The wheel 50 of highest order of the series at the opposite side is shown in Fig. II. The wheels 46, 47, and 48 are carried on the shaft 52 mounted in brackets 53, one of which is shown in Fig. II. The bank of oppositely counterpart wheels, including the wheel 50 of highest order, is carried by the shaft 54 mounted in brackets 55, one of which is shown in Fig. II. Necessary gearing connections are provided for connecting the numbered wheels with their gears 36, 37, and 38 of the quantity counter mechanism.

The sleeve 57, which is mounted to turn on the sleeve 24, has rigidly connected therewith the gear wheel 58 and the ratchet wheel 60, which ratchet wheel 60 is provided with a circular series of ten ratchet notches. Said wheels are connected by a series of rivets 62. The sleeve 63, likewise mounted to turn on said sleeve 24, also has connected therewith a similar gear wheel 58, and ratchet wheel 60.

Each of said gears 36, 37, and 38 carries a bell crank pawl 65 pivotally connected thereto on respective studs rigidly mounted on said respective gears 36, 37, and 38. The pawl tips are adapted to be engaged in notches, or slotted keyways, 68, in said sleeve 24 during the resetting to zero operation of the counter, as fully described in my copending application Serial No. 381,989.

Said gear 20 engages the gear 82 driving the variator mechanism generally indicated at B, and including the cone gear 83. The variator mechanism illustrated in Fig. I is of the type shown and described in Letters Patent of the United States No. 2,151,239, granted to Slye et al., but the improved means for adjusting the variator shown herein is the subject-matter of my invention.

The cone gear 83 drives three selector gears 84^a, and 84^b, which in turn drive the cost value gear 85 through differential or planetary gearing 86, all as fully described in said Slye et al. 75

Patent No. 2,151,239. The total cost register indicated generally by the reference mark E is driven through the clutch assembly 88 in the housing 89 on which said gear 85 is rigidly mounted by means of screws 90. Said clutch 88, similar to the clutch for the quantity register, includes clutch springs 91, clutch levers 92, pressure ring 93, clutch driving plate 95, and disk 96, which disk is interposed between the clutch plate 95 and the end closure plate 97 of said clutch housing 89. The clutch housing 89 is carried by the left hand end of the sleeve, or hollow shaft, 98, the right hand end of which is journaled in the side member 9, as indicated by the reference mark 99.

The hollow shaft 98 carries the clutch releasing plunger 100, the right hand end of which extends beyond the side frame member 9 for engagement with the bell crank lever arm 32'. The plunger rod 100 has mounted on the left hand end thereof the thimble 102 for engagement with the clutch levers 92, when said rod is moved to the left by operation of the zeroizing mechanism through rotation of the crank 35, all as described in my copending application Serial No. 381,989 which relates specifically to such zeroizing structure. Said thimble 102 is mounted for reciprocal movement in the bushing 103 carried by the left hand side frame member 8.

The counter mechanism is of ordinary construction and includes the gears 105, 106, and 107 mounted on said hollow shaft 98, and the tens transfer pinions 108 and 109. The transfer pinion 108 is loosely mounted on the shaft 110 rigidly supported in the bosses 111 formed on the top closure plate 6. Said transfer pinion 109 is loosely mounted on the shaft 113 rigidly supported in the bosses 114, also formed on the top closure plate 6.

Said total cost counter, generally indicated at E, includes two oppositely counterpart series of number wheels, one complete series of which is shown in Fig. I, including the wheel 116 of lowest order and conveniently carrying indicia indicating from "0" to "9" cents; the counter wheel 117 of next higher order, conveniently indicating from "0" to "9" tens of cents; and the counter wheel 118 of highest order, conveniently indicating from "0" to "9" dollars.

The wheel 119 of highest order, or the dollar wheel, of the series at the opposite side, is shown in Fig. II, the wheels 116, 117, and 118 being carried on the shaft 120 mounted in brackets 121, one of which is shown in Fig. II. The bank of oppositely counterpart wheels including the wheel 119 of highest order, is carried by the shaft 122 mounted in brackets 123, one of which is shown in Fig. II. Necessary gearing connections are provided for connecting the number wheels with their gears 105, 106, and 107 of the total cost register.

The price indicators include two oppositely counterpart series of number wheels 125, 126, and 127 and 125', 126', and 127'. The series of wheels 125, 126, and 127 are carried on the shaft 130, the opposite ends of which are journaled in bearing brackets 131 and 132 which are formed on the supporting plate 134 fastened to the side wall members 8 and 9. The series of wheels 125', 126', and 127' are carried on the shaft 130', the opposite ends of which are journaled in bearing brackets 131' and 132' which are formed on the supporting plate 134' fastened to the side wall members 8 and 9.

Said wheels 125 and 125' are the wheels of

lowest order, and conveniently carry indicia indicating tenths of a cent; said wheels 126 and 126' are the wheels of next higher order, and conveniently carry indicia indicating cents; and said wheels 127 and 127' are the wheels of highest order, and conveniently carry indicia indicating tens of cents. The wheel 125 is carried by the hub 135, which is mounted to turn freely on the shaft 130. Said wheel 125 is maintained in position on the shaft 130 by the collar 136 which is fastened to the shaft 130 by means of the set screw 137. Said hub 135 has formed at its right hand end, as shown in Fig. V, the gear 140. Thus, rotation of the gear 140 effects simultaneous rotation of the wheel 125. The gear 140 meshes with the bevel gear 141 which is rigidly mounted at one end of the shaft 142. Said shaft 142 is journaled in the supporting plates 134 and 134' mounted on opposite sides of said walls 8 and 9. Said shaft 142 has rigidly mounted thereon at its opposite end the bevel gear 146 in mesh with the gear 147 which is rigidly mounted on the sleeve 148. Said sleeve 148 is free to turn on the shaft 130' carrying the oppositely counterpart set of wheels 125', 126', and 127'. The wheel 125' is carried by and rigidly fastened to the opposite end of the sleeve 148.

The wheels 126 and 126' are respectively mounted on hubs 154 and 155. The hub 154, with the wheel 126 rigidly mounted thereon, is carried by and is free to turn on said shaft 130. The hub 155, with the wheel 126' rigidly mounted thereon, is carried by and is free to turn on said sleeve 148 carried by said shaft 131'. Said hub 154 has the gear 157 formed at the right hand end thereof, as shown in Fig. V. Said gear 157 meshes with the bevel gear 158 rigidly mounted at one end of the shaft 159, which is journaled in the brackets 134 and 134'. Said shaft 159 has rigidly mounted at its opposite end the gear 160 which meshes with the gear 161 formed at one end of the hub 155.

The wheel 127 has rigidly connected thereto the gear 162 and said wheel 127, including the gear hub 164, is mounted for freedom of turning movement on the shaft 130. Said wheel 127, and gear 162 with its hub 164, are maintained in position on the shaft 130 by means of the collar 165, which is conveniently rigidly fastened to the shaft 130 by means of the set screw 166. Said gear 162 meshes with the bevel gear 170 rigidly fastened to the shaft 171, which is journaled in the brackets 134 and 134'. The opposite end of said shaft 171 has rigidly mounted thereon the gear 172. Said gear 172 meshes with the gear 173 which is rigidly fastened to shaft 130', conveniently by means of the pin 175. The wheel 127' is rigidly mounted on the supporting hub 176, and said hub 176 is rigidly mounted on said shaft 130', conveniently by means of the pin 177.

Said shaft 142 has rigidly mounted thereon, intermediate of the gears 141 and 146, the sprocket gear 180. Said gear 180 is connected by the sprocket link chain 181 with the sprocket gear 182. Said sprocket gear 182 is rigidly fastened to one end of the shaft 183 which is journaled in the bearing bracket 186 rigidly connected to the bottom plate 5, conveniently by screws 187, one of which is shown in Fig. III. Said shaft 183 has rigidly mounted at the front end thereof the knurled knob 188.

Said shaft 159 has rigidly mounted thereon, intermediate of the gears 158 and 160, the sprocket gear 190, similar to the gear 180. Said gear 190 is connected by the sprocket link chain 75

191 with the sprocket gear 192. Said sprocket gear 192 is rigidly fastened to one end of the shaft 193 which is journaled in said bearing bracket 186. Said shaft 193 has rigidly mounted at the front end thereof the knurled knob 198.

Said shaft 171 has rigidly mounted thereon, intermediate of the gears 170 and 172, the sprocket gear 200, similar to the gears 180 and 190. Said gear 200 is connected by the sprocket link chain 201 with the sprocket gear 202. Said sprocket gear 202 is rigidly fastened to one end of the shaft 203 which is journaled in said bearing bracket 186. Said shaft 203 has rigidly mounted at the front end thereof the knurled knob 208.

The construction and arrangement is such that turning movement of the knob 188 effects simultaneous turning movement of the tenths cent indicator wheels 125 and 125'; turning movement of the knob 198 effects simultaneous turning movement of the cents indicator wheels 126 and 126'; and turning movement of the knob 208 effects simultaneous turning movement of the tens of cents indicator wheels 127 and 127'.

Said shaft 142 has rigidly mounted thereon the pinion 210 which is in engagement with the depending sliding rack 211 rigidly fastened by means of screws 212 to the reciprocating rod 213 which is journaled in bearings in the side frame members 8 and 9.

As best shown in Figs. IV and V, said rod 213 carries at its left hand end the bifurcated fork 214, conveniently rigidly fastened to said rod 213 by means of the screw 215. Said fork 214 engages the groove 216 of the supporting frame member 218 for the tenths cent selector gear 84. The selector gear 84 is journaled on the shaft 219 rigidly mounted at its opposite ends in the bearing arms 221 and 222 formed as part of said supporting frame member 218. Said supporting frame member 218 is mounted to slide axially on its keyed shaft 224, one end of which is journaled in the side frame member 8 and the other end of which is journaled in the variator side bearing plate 226. Said supporting frame member 218 is provided with the guide pin 228 which is rigidly fastened to the sliding bracket 229. The ends of the bracket 229 are formed in bights 230 and 231 for sliding guiding engagement with the U-shaped bail member 232 which is mounted for freedom of turning movement on the bushings in which the respective ends of the keyed shaft 224 are journaled. Said bail 232 is provided with the guide slot 235 in registry with the guide pin 228 carried by the supporting frame member 218.

Said sliding bracket 229 has rigidly mounted thereon the stud 240 adapted to be engaged with any one of the stepped series of notched recesses 241 in the arcuate guide plate 242 which is rigidly fastened by screws 243 to bosses 245 formed on the bearing plate 226. Engagement of the stud 240 with one of the notched recesses assures that the selector gear 84 is in full registry with the corresponding gear formed on the stepped gear cone 83. The bail 232 and supporting frame member 218, with its selector gear 84, are continually stressed counterclockwise by the spring 250, one end of which encircles the stud 251 rigidly mounted in the bail 232, and the other end of which spring 250 is rigidly fastened to the arcuate notched guide plate 252 forming part of the cents selector gear assembly. Thus, said selector gear 84 is continually stressed toward engagement with the stepped cone gear 83.

The stationary gear 255 is provided to engage

the selector gear 84 when the desired figure of the tenths cents is "0."

Each of said cents selector gear 84^a and the tens of cents selector gear 84^b is provided with an assembly identical to that above described with reference to the tenths of cents selector gear 84. The shifting assembly for the cents selector gear 84^a is mounted at the left hand end of the reciprocating rod 258 which is journaled in bearings in the side frame members 8 and 9. Said reciprocating rod 258 has formed on the underside thereof the sliding rack 260 for engagement with the pinion 261 which is rigidly mounted on the shaft 159.

The shifting assembly for the tens of cents selector gear 84^b is mounted at the left hand end of the reciprocating rod 262 which is journaled in bearings in the side frame members 8 and 9. Said reciprocating rod 262 has formed on the underside thereof the sliding rack 263 for engagement with the pinion 265 which is rigidly mounted on the shaft 171.

Referring more particularly to Fig. II; the selector gear release lever 267 is rigidly connected to the release ring 268 which is carried, in coaxial relation with the stepped cone gear 83, by a series of guide rollers 269 which are provided with grooved faces 270 which engage the inner circumference of said ring 268. Said groove guide rollers 269 are conveniently pivotally mounted on studs 272 screwed into the side frame member 8. Said ring 268 and lever 267 are continually stressed counterclockwise by the spring 273, one end of which encircles the stud 274 carried by the lever 267 and the other end of said spring 273 is connected to and encircles the stud 275 rigidly mounted in said side frame member 8.

Said release ring 268 is provided with a series of three studs 276 for engagement with the respective side members of the three bails 232 of the assemblies for the respective selector gears 84, 84^a, and 84^b. When said lever 267 is pushed to the left from the position shown in Fig. II, such movement of the lever 267 moves the release ring 268 clockwise on its guide rollers 269 and causes the studs 276 to come into engagement with the side members of the respective bails 232. Continued clockwise movement of said ring 268 causes the supporting frame members 218 to be swung clockwise about their respective shafts 224, thus simultaneously moving the selector gears 84, 84^a, and 84^b out of engagement with the stepped cone gear 83.

Operation of price changing mechanism

The price changing mechanism operates as follows when it is desired to effect a change in the rate at which the dollar register E computes in relation to the gallon register D:

The release lever 267 is pushed to the left in Fig. II by the operator, which causes the release ring 268 to move clockwise, in coaxial relation with the gear 83, around the series of grooved guide rollers 269. Such continued clockwise movement of the release ring 268 causes each of the three studs 276 to engage the side members of the bails of the assemblies for the respective selector gears 84, 84^a, and 84^b against the effective forces of their effective springs 259, and out of engagement with the stepped cone gear 83.

Each of said selector gears 84, 84^a, and 84^b, when thus held in disengaged position with respect to the cone gear 83 by continued pressure of the operator's thumb on the lever 267, is now free to be moved axially on its keyed shaft to a

changed position in registry with any one of the series of gear faces comprising the cone gear 83. Such axial movement of the selector gears is effected through turning movement of the knurled knobs 188 198, and 208 conveniently located at the bottom of the housing, as best shown in Fig. IV.

The tenths cent selector gear 84 is moved to changed position by turning movement of the knurled knob 188. Turning of the knob 188 causes the gear 182 to turn simultaneously, thus causing simultaneous movement of the gear 180 which is connected to the gear 182 by the sprocket chain 181. The gear 180 being fastened on the shaft 142 causes the gears 141 and 146 to move simultaneously with any movement of the gear 180. Such movement of the bevel gears 141 and 146 causes simultaneous movement of the gears 140 and 147. The gear 140 being fastened to the indicator wheel 125 and the gear 147 being fastened to the sleeve 148 carrying the wheel 125', said indicator wheels 125 and 125' move contemporaneously with any movement of the gear 182. The pinion gear 210 in engagement with the rack 211 carried by the reciprocating shaft 213, being likewise fastened to the shaft 142, turning movement of the gear 182 causes said reciprocating rod 213 to be moved either to the left or to the right in Fig. V in accordance with the direction in which the knurled knob 188 is turned by the operator. Movement of the reciprocating rod 213 causes the selector gear assembly to be moved on its keyed shaft 224 to the desired changed position in registry with the desired gear face of the cone gear. When the lever 267 and ring 268 are released by the operator, the selector gear assembly is moved counterclockwise by the effective forces of the spring 259. The stud 240 coming into engagement with the notch in the guide plate 242 assures the correct alignment of the selector gears with the desired gear face of the cone gear 83.

The selector gears 84^a and 84^b may be moved to changed position in exactly the same manner respectively by movement of the knurled knobs 198 and 208.

It is obvious from the foregoing description that the price indicator wheels and the selector gears are so interconnected that the selector gears must be in engagement with the proper gear of the cone gear to effect computation at the price displayed at the price indicator wheels, with the result that the total cost register must be the product of the displayed number of gallons dispensed multiplied by the displayed price per gallon.

After the selector gears have been moved to the desired changed positions, and the operator has released the pressure on the lever 267 to permit the selector gears to again go into engagement with the cone gear 83, the mechanism is then ready to compute at the price displayed on the price indicator wheels, except that the first succeeding dispensing operation will be in error the amount of the backlash entering the gear train during the price setting. Therefore, the mechanism should be run momentarily to take up the backlash, and thereafter the registers be reset to zero, as fully described in my copending application Serial No. 381,989. After the backlash has been thus taken up, the mechanism then will compute correctly at the changed price displayed at the price indicator wheels.

However, I do not desire to limit myself to the precise details of construction and arrangement

herein set forth, as it is obvious that various modifications may be made therein without departing from the essential features of my invention, as defined in the appended claims.

I claim:

1. In variating mechanism, adapted to operate registering means, including a drive shaft having a cone of gears of different diameters non-rotatably mounted thereon, a plurality of axially parallel supplemental shafts adjacent to said drive shaft, a driven member rotatably mounted on said drive shaft, and differential means rotatably mounted on said drive shaft and connecting said supplemental shafts to said driven member; the combination with a plurality of selector gears; of a plurality of selector gear sliding arm support assemblies, one of which is slidably mounted on each supplemental shaft; means normally effecting engagement of said selector gears with said cone gear; means for effecting substantially simultaneous disengagement of all of said selector gears from said cone gear; and means for effecting sliding movement of each selector gear when in disengaged position, including a rack shaft in operating relation to each of said selector gears and a pinion gear in operating relation to each of said rack shafts.

2. A structure as in claim 1; wherein the means for effecting substantially simultaneous disengagement of all of said selector gears from said cone gear includes a lever; a release ring connected to said lever; and means connected to said release ring for engagement with said sliding arm support assemblies.

3. A structure as in claim 1; wherein the means for effecting substantially simultaneous disengagement of all of said selector gears from said cone gear includes a lever; a release ring connected to said lever; and studs mounted on said release ring for engagement with said sliding arm support assemblies.

4. In variating mechanism, adapted to operate registering means, including a drive shaft having a cone of gears of different diameters non-rotatably mounted thereon, a plurality of axially parallel supplemental shafts adjacent to said drive shaft, a driven member rotatably mounted on said drive shaft, and differential means rotatably mounted on said drive shaft and connecting said supplemental shafts to said driven member; the combination with a plurality of selector gears; of a plurality of selector gear sliding arm support assemblies, one of which is pivotally slidably mounted on each supplemental shaft; a U-shaped bail member mounted for freedom of turning movement on each supplemental shaft; a guide slot in said bail member; a guide pin carried by each assembly for guiding engagement with said bail member guide slot; means normally effecting engagement of said selector gears with said cone gear; means for effecting substantially simultaneous disengagement of all of said selector gears from said cone gear; and means for effecting sliding movement of each selector gear when in disengaged position, including a rack shaft in operating relation to each of said selector gears and a pinion gear in operating relation to each of said rack shafts.

5. A structure as in claim 4; wherein the means for effecting substantially simultaneous disengagement of all of said selector gears from said cone gear includes a lever; a release ring connected to said lever; and means connected to said release ring for engagement with said sliding arm support assemblies.

6. A structure as in claim 4; wherein the means for effecting substantially simultaneous disengagement of all of said selector gears from said cone gear includes a lever; a release ring connected to said lever; and studs mounted on said release ring for engagement with said bail members.

7. In variating mechanism, adapted to operate registering means, including a drive shaft having a cone of gears of different diameters non-rotatably mounted thereon, a plurality of axially parallel supplemental shafts adjacent to said drive shaft, a driven member rotatably mounted on said drive shaft, and differential means rotatably mounted on said drive shaft and connecting said supplemental shafts to said driven member; the combination with a plurality of selector gears, of a plurality of selector gear sliding arm support assemblies, one of which is slidably mounted on each supplemental shaft; means normally effecting engagement of said selector gears with said cone gear; means for effecting substantially simultaneous disengagement of all of said selector gears from said cone gear; means for effecting sliding movement of each selector gear when in disengaged position, including a rack shaft in operating relation to each of said selector gears; a pinion gear shaft for each rack shaft; a pinion gear rigidly mounted on each pinion gear shaft and in operating relation to each of said rack shafts; a price indicator carrying numerical indicia for each pinion shaft; means connecting said price indicators with said pinion gear shafts; whereby movement of a pinion gear effects simultaneous movement of its price indicator so that the displayed indicia coincides with the corresponding setting of the selector gear in its engaging position with the selected gear of said cone of gears.

8. In variating mechanism, adapted to operate registering means, including a drive shaft having a cone of gears of different diameters non-rotatably mounted thereon, a plurality of axially parallel supplemental shafts adjacent to said drive shaft, a driven member rotatably mounted on said drive shaft, and differential means rotatably mounted on said drive shaft and connecting said supplemental shafts to said driven member; the combination with a plurality of selector gears, of a plurality of selector gear sliding arm support assemblies, one of which is slidably mounted on each supplemental shaft; spring means normally effecting engagement of said selector gears with said cone gear; means for effecting substantially simultaneous disengagement of all of said selector gears from said cone gear; means for effecting sliding movement of each selector gear when in disengaged position, including a rack shaft in operating relation to each of said selector gears; a pinion gear shaft for each rack shaft; a pinion gear rigidly mounted on each pinion gear shaft and in operating relation to each of said rack shafts; a second shaft, having a knob at the exterior end, for effecting manual rotation of said pinion shaft, including means connecting said pinion gear shaft and said second shaft; a price indicator carrying numerical indicia for each pinion shaft; means connecting said price indicators with said pinion gear shafts; whereby movement of a knob effects simultaneous movement of its price indicator so that the displayed indicia coincides with the corresponding setting of the selector gear in its engaging position with the selected gear of said cone of gears.
